DISPLAY STAND FOR MECHANIC'S HAND TOOLS

Robert L. Daugherty, Oswego, Oreg., assignor to Pendleton Tool Industries, Inc., Los Angeles, Calif., a corporation of California

Filed Mar. 7, 1960, Ser. No. 59,654

Term of patent 14 years

(Cl. D80—9)

Fig. 1

Fig. 3

Fig. 2

Fig. 1 is a front perspective view taken from the top of a display stand for mechanic's hand tools, showing my new design;

Fig. 2 is a top plan view thereof;

Fig. 3 is a front elevational view thereof;

Fig. 4 is a right side elevational view thereof;

Fig. 5 is a left side elevational view thereof; and

Fig. 6 is a horizontal cross-sectional view thereof taken on line 6—6 of Fig. 4.

I claim:

The ornamental design for a display stand for mechanic's hand tools, as shown.
